DUNE BUGGY BODY

Michael Gale Black, 8401 Wheatland,
Sun Valley, Calif. 91352

Filed May 19, 1969, Ser. No. 17,214

Term of patent 14 years

Int. Cl. D12—08

U.S. Cl. D14—3

FIG. — 1

FIG. — 2

FIG. — 3

FIG. - 4

FIG. - 5

FIG. - 6

FIG. 1 is a front side perspective view of the dune buggy body embodying my new design.

FIG. 2 is a rear side perspective view of the dune buggy body.

FIG. 3 is a side elevational view of the dune buggy body.

FIG. 4 is a front view of the dune buggy body.

FIG. 5 is a rear view of the dune buggy body.

FIG. 6 is a plan view of the dune buggy body.

I claim:

The ornamental design for a dune buggy body, substantially as shown and described.
